UNITED STATES PATENT OFFICE.

HUZEB A. MALO, OF HAMMOND, INDIANA.

HORSESHOE.

1,043,856.

Specification of Letters Patent. Patented Nov. 12, 1912.

Application filed June 12, 1912. Serial No. 703,231.

To all whom it may concern.

Be it known that I, HUZEB A. MALO, a citizen of the United States, residing at Hammond, in the county of Lake and State 5 of Indiana, have invented certain new and useful Improvements in Horseshoes, of which the following is a specification.

This invention relates to that class of horseshoes which are in sections, one section 10 being permanently secured to the animal's hoof and the other being attached in such a manner that it may be removed and renewed when it becomes worn.

It is the object of the invention to provide in a shoe of the kind stated, an improved fastening for the removable section, whereby said section may be easily and quickly detached and renewed, and also to provide a structure which adapts the shoe 20 to different sized hoofs, as well as to hoofs which are sore and cannot endure pressure.

In order that the invention may be better understood, reference is had to the accompanying drawing, in which—

25 Figure 1 is a bottom plan view of the shoe. Fig. 2 is a section on the line 2—2 of Fig. 1. Fig. 3 is a perspective view of the removable or tread portion of the shoe. Fig. 4 is a perspective view of the front portion of the 30 permanent section of the shoe. Fig. 5 is a perspective view of a connecting plate.

Referring specifically to the drawing, 10 denotes that section of the shoe which is permanently fastened to the animal's hoof.

35 The detachable section is indicated at 11, said section being provided with a toe-calk 12 and heel-calks 13. The toe portion of the section 11 has a tongue 14 projecting inward from its inner edge, and at the outer edge of said section, on top thereof, is an upstanding flange 15 which fits around the outer edge of the section 10 and holds the section 11 against lateral movement. The section 10 has nail-holes 16 and is adapted 40 to be nailed on the hoof in the same manner as any ordinary shoe. On the bottom of the section 10, at the toe-portion thereof, is a lug 17, having an opening 18 through which the tongue 14 passes, whereby the toe-portion

50 of the section 11 is made fast to the corresponding portion of the section 10. The section 10 also has the usual toe-piece 19.

At the heel portions of the section 10 are depending studs 20 which pass into apertures 21 in the corresponding portions of the 55 section 11. The outer ends of the studs have threaded apertures to receive screw bolts 22, whereby the heel portions of the section 11 are held against separation from the corresponding portions of the section 10, the 60 heads of the screw bolts engaging the bottom of the section 11. The studs 20 are also connected by a transverse plate or bar 23, the ends of the latter having slots 24 to receive the studs. The heel-portions of the 65 section 10 are reduced in thickness, as indicated at 25, and the ends of the plate 23 lie between said reduced portions and the heel-portions of the section 11. By thus reducing the heel-portions of the section 10 to 70 accommodate the plate 23, the section 11 may be level with the section 10. The slots 24 allow the heel-portions of the sections to be brought closer together or spread, according to the width and condition of the hoof. 75 The plate 23 has an intermediate enlarged portion 26 which is bent upward to come flush with the top of the section 10, and against the bottom of the hoof, as shown by dotted lines in Fig. 2, so that a front rest 80 for the same is had.

Between the sections 10 and 11 is interposed a gasket 27 of rubber or other suitable cushioning material to deaden the noise and cushion the tread-section 11 of the shoe. 85

By the herein described fastening the tread-section of the shoe can be easily and quickly detached and renewed, and said section can also be readily adjusted to different sized hoofs, or hoofs that are sore and cannot stand pressure.

I claim:

A horse-shoe comprising hoof and tread sections, the heel portions of the hoof section being reduced in thickness, and having depending studs the outer ends of which having threaded apertures, and the corresponding portions of the tread section having

apertures to receive the studs, bolts screwed into the apertures of the studs, the heads of said bolts engaging the bottom of the tread section, a detachable connection between the 5 toe-portions of the sections, and a transverse bar between the heel portions of the sections, said bar seating in the reduced portion of the hoof section and having an in-

termediate portion extending upward in contact with the bottom of the hoof.

In testimony whereof I affix my signature in presence of two witnesses.

HUZEB A. MALO.
